UNITED STATES PATENT OFFICE.

JEREMIAH QUINLAN, OF NEW YORK, N. Y.

DESIGN FOR A FLASK.

SPECIFICATION forming part of Design No. 33,363, dated October 16, 1900.

Application filed August 4, 1900. Serial No. 25,953. Term of patent 3½ years.

To all whom it may concern:

Be it known that I, JEREMIAH QUINLAN, a citizen of the United States, and a resident of the city of New York, borough of Manhattan, 5 in the county and State of New York, have invented and produced a new and original Design for a Flask, of which the following is a specification, reference being had to the accompanying drawings, forming a part there-
10 of, in which—

Figure 1 is a front elevation of a flask embodying the features of my design, and Fig. 2 is a transverse section taken on the line 2 2 of Fig. 1.

15 The design consists of a flask, which, in general outline, simulates a shirt, and of a cap at one end of the said figure.

In the detail formation of the flask the body represents the bosom, back, skirt, and neck-

bands of a top shirt, the cap mentioned ap- 20 pearing at the neckband portion of the body, and series of lines at each side of the body are so grouped and drawn that they represent the sleeves of a shirt. In cross-section the body presents an oblong central figure and 25 connecting semicircular side figures.

Having thus described my invention, I claim as new and desire to secure by Letters Patent—

The design for a flask herein shown and de- 30 scribed.

In testimony whereof I have signed my name to this specification in the presence of two subscribing witnesses.

JEREMIAH QUINLAN.
